Primary Examiner—Dominic Simone

Attorney, Agent, or Firm—Patent & Trademark Services;
Joseph H. McGlynn[57] **CLAIM**

The ornamental design for a boot protector, as shown and described.

DESCRIPTION

FIG. 1 is a top plan view of a boot protector showing my new design;

FIG. 2 is a right side elevational view thereof, the left side being a mirror image;

FIG. 3 is a front elevational view thereof; and,

FIG. 4 is a top plan view thereof on a reduced scale, the boot shown in broken lines for illustrative purposes only and forms no part of the claim.
